UNITED STATES PATENT OFFICE.

EARL B. FRENCH, OF OAKLAND, CALIFORNIA.

FEED-TROUGH.

SPECIFICATION forming part of Letters Patent No. 473,735, dated April 26, 1892.

Application filed August 12, 1891. Serial No. 402,414. (No model.)

To all whom it may concern:

Be it known that I, EARL B. FRENCH, of 5
Oakland, in the county of Alameda and State
of California, have invented a new and Im-
proved Feed-Trough, of which the following
is a specification, reference being had to the
annexed drawings, forming a part thereof, in
which—

Figure 1 is a front elevation of my improved
10 feed-trough. Fig. 2 is a perspective view
showing the lid of the trough open. Fig. 3 is
a vertical transverse section. Fig. 4 is a front
perspective view showing the partition re-
moved, and Fig. 5 is a rear view of the parti-
15 tion and the lid.

Similar letters of reference indicate corre-
sponding parts in all the views.

The object of my invention is to provide a
20 simple feed-trough in which the feed will be
supplied gradually, so that the animal will be
compelled to eat his food slowly and thor-
oughly masticate it, thereby securing the full
value of the food.

My invention consists of a feed bowl or
25 trough having a side reservoir separated from
the bowl by a removable partition and ratchet
mechanism for holding the partition in posi-
tion in the reservoir, all as will be hereinafter
more fully described.

30 The feed-trough consists of three principal
parts: the bowl A, the reservoir B, and the
partition C. The bowl A, which is oblong in
form, is provided with a rounded bottom and
an inclined rear side a. To the inclined rear
35 side is secured the reservoir B by means of
bolts or rivets, as shown. The upper portion
of the reservoir B is inclined and the forward
portion is provided with inwardly-turned
ledges b for receiving the partition C, which
40 is slid down behind the said ledges.

To the upper end of the partition C is
hinged the lid D, which is open-ended and is
provided with end flanges adapted to shut
45 down inside of the reservoir. The cover D,
when swung open, as shown in Fig. 2, serves
as a chute for conducting the grain to the
hopper. The inner face of the partition C is
provided with a ratchet c and with two pairs
50 of lugs d. To a lug e, projecting forward from
the back of the reservoir, is pivoted a pawl f,
which is adapted to engage the ratchet c on
the inner face of the partition, and studs g

project inwardly from the sides of the reser-
voir within the ledges b. These studs are ar-
ranged with reference to the lugs d, so that 55
when the partition is pushed inwardly the
said lugs d will engage the studs g and pre-
vent the partition from further movement in
that direction and from being raised. When
the partition is inserted in its place in the 60
reservoir, a small space is left between the
lower end thereof and the bottom of the reser-
voir for the escape of feed from the reservoir
into the bowl A, and the pawl f occupies an
inclined position in the reservoir, as shown in 65
Fig. 3, so that when the partition is pushed
inwardly by the animal the tendency is first
to raise it by the action of the pawl and thus
increase the flow of feed to the bowl of the
trough. A further movement brings the lugs 70
d into engagement with the studs g and pre-
vents any further lifting of the partition.
When the trough is used for feeding roots
and vegetables, the partition C is removed.

It will be observed that my improved feed- 75
trough is to a certain extent automatic in
its action, while at the same time it is con-
trollable by the animal feeding from the
trough.

The movement of the partition by the ani- 80
mal prevents the trough from clogging, and
the adjustment of the partition provides for
different kinds of food.

Having thus described my invention, I
claim as new and desire to secure by Letters 85
Patent—

1. In a feed-trough, the combination, with
a bowl, of a hopper at one side of the bowl,
and having a vertically movable and swing-
ing partition extending down to within a short 90
distance of the bottom of the bowl, substan-
tially as and for the purpose set forth.

2. In a feed-trough, the combination, with
a bowl, of a hopper at one side of the bowl, a
swinging partition in the front of the hopper 95
and extending down to within a short distance
of the bottom of the bowl, and means for im-
parting a vertical movement to the said par-
tition when pressure is applied thereto to
swing it inward, substantially as described. 100

3. In a feed-trough, the combination, with
a bowl and a hopper at one side of the bowl
and discharging into the said bowl, of a cover
having flange sides and open ends and hinged

to the front of the hopper, whereby the cover is made to serve both as a cover and a chute, substantially as described.

4. The combination, with the bowl A, provided with the reservoir B, of the partition C, furnished with the ratchet c, and the pawl f, connected with the reservoir and adapted to engage the ratchet, substantially as specified.
5. The combination of the bowl A, the reservoir B, provided with the studs g, the partition C, provided with the ratchet c and lugs

d, and the pawl f, adapted to engage the ratchet, substantially as specified.

6. The combination of the bowl A, the reservoir B, having inwardly-turned edges b and the studs g, the partition C, provided with the ratchet c and lugs d, and the lid D, hinged to the partition C, substantially as specified.

EARL B. FRENCH.
